EXPANSIBLE BIT.

1,071,202.

Specification of Letters Patent.

Patented Aug. 26, 1913.

Application filed May 14, 1913. Serial No. 767,551.

To all whom it may concern:

Be it known that I, GEORGE P. BUTLER, a citizen of the United States, residing at Wallingford, county of New Haven, and 5 State of Connecticut, have invented certain new and useful Improvements in Expansible Bits, fully described and represented in the following specification and the accompanying drawings, forming a part of the 10 same.

This invention relates to improvements in expansible bits and particularly to an expansible bit which may be used for boring a hole with a reverse taper.

15 The especial object of the invention is to provide an improved expansible bit, that shall be efficient in action and durable, while at the same time simple and cheap of manufacture, and in which the cutter shall be 20 laterally adjustable by the rotation of the bit, so as to be automatically adjusted to expand the bore at the proper rate relatively to the speed of the bit, by intermittently advancing the cutter as the bit rotates. 25 A further object of the invention is to provide an expansible bit in which the cutter may be adjusted readily to cut any desired size of hole within its range of sizes, and also may be quickly and easily removed 30 and replaced as, for example to sharpen said cutter or replace it when broken.

With the above, and some further objects which will be apparent to those skilled in the art from the description hereinafter 35 given, an expansible bit embodying the broad features of my invention comprises a cutter adjustable laterally and reciprocating means for intermittently feeding said cutter laterally a predetermined amount at prede- 40 termined intervals.

A device embodying the best form of my invention comprises a cutter, manually-operable means for adjusting said cutter laterally, and a reciprocatory device arranged 45 to engage and move said adjusting means at intervals, whereby the cutter is fed laterally. By this arrangement, the cutter may be adjusted manually to the desired size without manipulating the reciprocatory device, and 50 in the best embodiment of the invention, the construction is such that the reciprocatory device in its retracted or non-actuating position leaves the cutter adjusting means free for such manual adjustment of the cutter,

whereby unnecessary friction is avoided and 55 the removal and replacement of the cutter is simplified.

The invention will now be described in its preferred embodiment as shown in the accompanying drawings, in which—

60 Figure 1 is an elevation of the complete bit, with the sleeve partly in section. Fig. 2 is a central longitudinal section of the sleeve at right angles to Fig. 1, with the pawl rod and cutter portion of the bit in elevation. 65 Figs. 3, 4 and 5 are cross sections on the lines 3—3, 4—4, and 5—5 of Fig. 2. Fig. 6, is a longitudinal section on the line 6 of Fig. 1, on an enlarged scale. Fig. 7, is a central section at right angles to Fig. 6, with 70 the cutter and worm in elevation. Fig. 8 is a detail section on one side of the pawl rod and ratchet.

75 Referring to the drawings, 1 is a bit shank, in the present example shown as provided with the usual squared and tapered socket-engaging end integral with the shank, and also having an enlarged bit-head 2, below which is arranged a means for feeding the bit into the material; this means comprising, 80 in the form shown, a gimlet screw 3, above which is a center-cutter having a cutting edge indicated at 4, above which is arranged a spiral channel for the escape of the chips from said cutting edge 4. The center-cutter 85 also may be provided with a scoring-lip 5. Above the center-cutter the bit-head 2 carries a laterally movable cutter 6 and means for feeding said cutter laterally. In the embodiment shown the bit-head 2 is flattened 90 on one side and provided with square dove-tailed grooves, and the cutter 6 is formed to fit into said grooves, as will be clear from Figs. 2 and 6 of the drawings. The cutter 95

6 has the usual cutting edge 7 and scoring- 95 lip 8, the cutting edge projecting from the plane of the front surface of the cutter and being connected therewith by a curved surface over which the chips from the said cutting edge 7 are gradually deflected. Just 100 above the said cutter 6 the bit-head is provided with means for adjusting and holding the cutter, this means, in the embodiment shown, consisting of a worm 9 arranged with its axis transverse to the axis of the bit-shank, said worm being arranged in a socket in the bit-head and having its lower side in mesh with a worm-rack 10, Fig. 7, formed

on the upper edge of the cutter 6. At one end of the worm 9 is a ratchet wheel 11, the worm and ratchet wheel being carried by stub-shaft 13, mounted in the bit head.

5 The socket in the bit-head, in which the worm with its connected parts is mounted, has a reduced bore at its inner end in which the inner end of stub-shaft 13 is rotatable, and at its outer end is counter-bored, said 10 counter-bore portion 14 being threaded to receive an externally-threaded collar 15, which can be slipped onto the stub-shaft 13 and then screwed into the counter-bore of the socket, the collar thereby serving as an 15 outer bearing for the stub-shaft 13. For the purpose of allowing the worm to be manually operated the stub-shaft 13 has its outer end suitably formed to receive an operating tool, as for example, by providing the outer 20 face of the stub-shaft 13 with a slot as shown, into which the end of an ordinary screw-driver or the like tool may be inserted. The collar 15, Fig. 2, also is preferably formed to be engaged by a suitable tool for 25 rotating it, when screwing it into or unscrewing it from the counter-bore, as for example, by slotting the outer face of said collar to receive a screw-driver.

It is to be noted that in the preferred 30 embodiment of the invention illustrated in the drawings, the outer faces of the collar 15 and the stub-shaft 13 do not project beyond the surface of the bit-head, the outer surface of the collar being curved and continuous 35 with the outer surface of the bit-head, while the outer face of the stub-shaft is substantially tangent to the curved outer surface of the collar, whereby a substantially smooth exterior is provided.

40 It will be seen that by applying a screw-driver to the slotted end of the stub-shaft 13, the latter, and with it the worm and the ratchet wheel, may be rotated, and owing to the engagement of the worm with the 45 worm-rack of the cutter, the latter may be moved inward or outward, assuming that the ratchet-wheel is not engaged in any way. Furthermore, by running the cutter out to its extreme limit, the teeth of its worm-rack will finally leave the worm-wheel and the cutter may then be freely drawn out of the guideways of the head, so that the cutter may be sharpened and then replaced by a reversion of the steps described. In the 50 best embodiment of the invention, the pitch of the worm is so flat that end thrust on the cutter cannot cause the rotation of the worm, that is to say, the worm and the worm-rack on the cutter constitute a self-locking adjusting means or device so that 55 the cutter cannot be moved from any position to which it is adjusted except by purposely rotating the worm by a tool applied to the stub-shaft 13.

60 For the purpose of actuating the worm

during the rotation of the bit, in order to automatically produce a reverse taper in the hole being bored, suitable means is provided whereby an intermittent rotation may be given to the worm. This means comprises, in the present example, the ratchet-wheel 11 and a device for converting rotary motion of the bit into reciprocatory motion and comprising a reciprocatory member 65 engaging the ratchet-wheel to cause the desired intermittent rotation of the worm. In the embodiment shown in the drawings, the device for converting rotary into reciprocatory motion comprises a cam device and a reciprocatory member arranged to engage 70 the cam device, one of these two devices being stationary and the other having an angular motion relative to it. In the specific construction shown in the drawings, the bit-shank is slotted longitudinally in 75 line with the ratchet-wheel 11, and in this slot is slidably mounted a pawl-rod 16, which is provided with a shoulder 17, Fig. 8, arranged to engage the teeth of the ratchet-wheel. The upper end of the pawl-rod has a laterally or radially projecting 80 pin 18, which may carry an antifriction roller 19 arranged to be engaged by a suitable cam device. In the present example 85 this cam device is formed as follows: The bit shank is enlarged in diameter at two places as indicated at 20 and 21, Figs. 1, and 2, these enlargements serving as collars, between which are placed two tubular sheaths 90 22 and 23 having those ends next to the respective collars 20 and 21 square, while the ends of said sheaths which are adjacent to each other are sloped to form cam edges 24, said edges being parallel to each other and separated a distance about equal to the diameter of the roller 19 on the pawl-rod, so that 95 said roller may travel in the space between said cam edges 24. As the interior diameter of each sheath 22 and 23, is substantially equal to the external diameter of the 100 bit-shank, and as the enlargements or collars 20 and 21 are, in the present instance, integral with the bit-shank, each of the said sheaths must be split longitudinally as 105 shown in Figs. 1 and 3 in order to permit them to be put in place on the shank. Over the bit-shank is placed a sleeve 25, arranged to surround both collars 20, 21 and to enclose the tubular sheaths. The exterior surface of this sleeve 25, is milled and serves as 110 a hand-hold in operating the device for boring holes with a reverse taper. The sleeve is held in place on the shank while permitting rotation of the bit-shank relative thereto, and the sleeve is attached to the 115 sheaths 22 and 23 by machine screws 26, 27, threaded into the sleeve from opposite sides with the ends of the screws entering holes in the respective sheaths.

120 It will be obvious that, when the bit- 130

shank is rotated, the pawl-rod 16 will be carried around with the bit-shank. If the sleeve 25 is free to rotate with the bit-shank no reciprocating movement of the pawl-rod 3 will occur, but if said sleeve be held stationary, the sheaths also will be stationary, and as the pawl-rod and its roller 19, rotate with the bit, the roller 19 and pawl-rod 16 will be reciprocated by the cam 24 and the 10 pawl-rod will operate the ratchet-wheel to rotate the worm and secure the outward feed of the cutter. With the cutter shown, which is self-feeding outward, the worm acts to hold the cutter against outward 15 movement, and when moved releases the cutter for the outward feed. This is preferable as it reduces the wear on the parts, but other forms of cutters may be used and the worm feed the cutter by forcing it outward. 20 For the purpose of allowing the pawl-rod to yield and thereby clear the teeth of the ratchet-wheel on its stroke, the pawl-rod is fitted with a slight radial clearance beneath the lower sheath and the sleeve, so 25 that it may move radially outward to a slight extent during its reciprocation, and for the purpose of holding the said pawl-rod yieldingly against the ratchet-wheel a suitable spring device is employed. In the 30 present example, this spring device consists of a substantially circular spring 28 retained in a circumferential groove 29, formed in the lower collar 21, and covered by the lower end of the sleeve, this spring 28, having one end inserted in a radial hole in the shank and the other end arranged to rest upon the pawl-rod, as will be clear from Fig. 5. Any suitable friction or other holding device may be used for preventing the 35 ratchet-wheel being rotated backward by the pawl-rod 16 as the latter is withdrawn. As shown, this result is secured by a coil spring 30 pressing against the end of the stub-shaft 13 and pressing the worm 9 against 40 disk 15.

It is to be understood that the bit disclosed may be used as an ordinary expandable bit for boring holes of different sizes within range of the adjustment of the cutter 6. The cutter may be adjusted either 50 inward or outward by turning the stub-shaft 13 and its attached worm in the proper direction, which is possible when the pawl-rod 16 is fully retracted upward because at 55 this time the pawl-shoulder 17 is out of the orbit of the teeth of the ratchet-wheel, thus leaving the said ratchet-wheel free to rotate in either direction. During the use of the bit for boring straight, that is, non-tapering holes, the sleeve 25 is not held, but 60 is allowed to turn with the bit-shank, whereby the pawl-rod is not reciprocated. When it is desired to bore a tapered hole the cutter 6 is first adjusted to the desired starting position and during the rotation of the 65

bit, the sleeve 25 is grasped by the hand of the operator and held stationary, whereby the tubular sheaths 22 and 23 are also held stationary, thus causing the roller 19 on the pawl-rod to ride around in the cam slot formed between the ends of the tubular sheaths. In this way the pawl-rod is reciprocated. The rate of reciprocation of the pawl-rod depends on the particular configuration of the cam slot. In the example given, the cam slot is a simple incline up and down and therefore there is only one reciprocation for each rotation of the bit-shank. The result of this movement of the pawl-rod in the specific example illustrated 70 is to move the ratchet-wheel one tooth for each rotation of the bit, thereby rotating the worm and feeding the cutter laterally outward a predetermined amount for each rotation of the bit-shank, the extent of this 75 predetermined feed depending upon the number of teeth of the ratchet-wheel. Instead of feeding the cutter outward to gradually enlarge the hole, it will be understood that the bit may readily be arranged 80 by proper construction and arrangement of ratchet-wheel, worm and rack, or substitution of parts, to feed the cutter laterally inward and form a hole tapering inward from a larger to a smaller diameter. It is obvious 85 that interchangeable cutters of different sizes or different forms may be used, so that by substitution of cutters, a very wide range 90 of work may be provided for.

It will be seen from the drawings, that 100 the specific embodiment of the invention is a compact, durable device readily operated, adjusted and sharpened, but it will be understood that the invention is not to be limited to the exact construction or arrangement of parts shown, but that modifications may be made therein without departing 105 from the invention.

Having thus fully described my invention, what I claim is:—

1. In an expandible bit, the combination, with a bit-shank and a laterally-adjustable cutter carried thereby, of manually-controllable reciprocatory means for intermittently feeding said cutter laterally a predetermined 115 amount at predetermined intervals by the rotation of the bit.

2. In an expansion bit, the combination, with a bit-shank and a laterally-adjustable cutter carried thereby, of manually-operable 120 means for adjusting said cutter, and manually-controllable reciprocatory means for intermittently feeding said cutter laterally a predetermined amount at each revolution of the bit-shank.

3. In an expandible bit, the combination, with a bit-shank and a laterally adjustable cutter carried thereby, of a manually-operable self-locking means for adjusting said cutter laterally, and manually-controllable 130

reciprocating means actuated by the rotation of the bit-shank for actuating said adjusting means, whereby the cutter is fed laterally.

4. In an expansible bit, the combination, 5 with the bit-shank, and a laterally adjustable cutter carried thereby and having a worm-rack, of a worm carried by the bit and engaging the worm-rack, a ratchet-wheel connected to the worm and arranged 10 to drive the same, a pawl-rod engaging the ratchet-wheel, and a cam device arranged to reciprocate the pawl-rod when the bit is rotated.

5. In an expansible bit, the combination, 15 with a bit-shank, a laterally adjustable cutter carried thereby and means for adjusting said cutter laterally, of a means including a reciprocating device for actuating said cutter-adjusting means, said means being carried by the bit-shank, and cam-mechanism 20 arranged to be held stationary and thereby to reciprocate the reciprocating device.

6. The combination with a bit and a laterally adjustable cutter carried thereby, of a 25 rack on the cutter, worm 9 engaging the rack, pawl wheel 11 on the worm shaft, pawl-rod 16 for rotating the wheel, and

means for reciprocating the pawl-rod by the rotation of the bit.

7. The combination with a bit and a laterally adjustable cutter carried thereby, of a 30 rack on the cutter, worm 9 engaging the rack, pawl wheel 11 on the worm shaft, pawl-rod 16 for rotating the wheel, a cam 35 engaging the pawl-rod, and hand sleeve 25 for holding the cam stationary or permitting it to rotate with the bit.

8. The combination with a bit and a laterally adjustable cutter carried thereby, of a 40 rack on the cutter, worm 9 engaging the rack, pawl-wheel 11 on the worm shaft, pawl-rod 16 for rotating the wheel, sectional 45 sheaths 22, 23 inclosing the bit stem and forming cam 24 engaging the pawl-rod, and hand sleeve 25 detachably connected to the sheaths for holding the cam stationary or permitting it to rotate with the bit.

In testimony whereof, I have hereunto set my hand, in the presence of two subscribing witnesses.

GEORGE P. BUTLER.
